[57] **ABSTRACT**

A flexible drawback assembly for use in a package tying machine, the assembly being connected to the twine wrapper arm of the tying machine for rotation therewith, and including a connector stem, resilient flexor means, and an extended drawback lever terminating in a string-guide eyelet. The flexible drawback assembly is resiliently operable and laterally deflectible to maintain a desired running tension on the twine while simultaneously taking up excess slack, and further provides extended take-up capabilities since it is relatively unaffected by centrifugal forces, quickly reacts to twine slack variations, and inherently limits its own range of travel in relation to the wrapper arm.

FIG. I

FIG.
3

FIG. 2

FLEXIBLE DRAWBACK ASSEMBLY FOR PACKAGE TYING MACHINE

BACKGROUND OF THE INVENTION

1. Field of the Invention

This invention relates generally to automatic tying machines and more particularly to improved drawback means for tensioning the materials used therein.

2. Description of the Prior Art

Prior art bundle and package tying machines are typically fitted with a drawback assembly to automatically tension and take up excess slack in the twine as a reach of the twine is being wrapped around a bundle. Reference is made to U.S. Pat. Nos. 1,606,290, dated Nov. 9, 1926, and 2,898,847, dated Aug. 11, 1959, wherein the operating sequence of a typical package tying machine is disclosed. Reference is also made to U.S. Pat. Nos. 1,994,453 dated Mar. 19, 1935, and 2,371,024, dated Mar. 6, 1945, which disclose a drawback assembly utilizing a rigid drawback lever, spring anchor bracket, and tension spring means. In the latter patent in particular, the drawback arm is freely rotatable with the twine wrapper arm and is pivotally mounted on the latter's base; the overall range of operating movements in relation to the machine's wrapper arm is limited by angularly extending fingers.

At the start of a wrapping operation for a typical bundle tying machine as therein described, the initial pull on the twine pulls the drawback lever into generally parallel alignment with the radial reach of the wrapping arm. As the twine begins to catch up with the wrapper arm, spring biasing forces on the drawback lever return the drawback lever to an acute operating alignment position with respect to the wrapper arm. In this normal operating position, while additional twine is drawn from the twine feeder mechanism, the drawback assembly automatically takes up slack within certain inherent limits. Simultaneously, the drawback assembly tends to maintain a predetermined running tension on the twine during wrapping of a bundle.

Because a package tying machine must be able to wrap and tie a reach of twine around bundles of various sizes, the drawback assembly for the wrapper arm must be capable of proportionally varying amounts of twine slack dependent on package size. Because the drawback levers of prior art drawback assemblies have been of rigid construction, certain take up limits (both as to speed of take-up and length of take-up) have been inherently placed on the drawback levers, due on a large part to the tremendous centrifugal forces developed on them during high speed wrapping. Moreover, because the tensioning take-up forces of the prior art drawback assemblies did not directly act on the twine to provide drawback take-up, but rather acted indirectly through a series of levers and pivots, these prior art assemblies were limited in the degrees of travel through which they operated in relation to the wrapper arm, in the maximum rotational speeds allowed, and in the speed of recovery after initial wrapper arm start up. The above-mentioned indirect drawback and tensioning further limited the length of drawback capability for a specific length drawback lever. Since these various limitations in combination limited the range of package sizes capable of being wrapped and tied by a specific size package tying machine, an operator required several different size machines in order to handle a full range of package sizes. A further problem with the

prior art drawback assemblies centered about the tension spring for the drawback lever which invariably broke because of repetitive changes in required tension.

SUMMARY OF THE INVENTION

The present invention overcomes the aforesaid defects of the prior art and is successfully adaptable to many of the various prior art package tying machines.

A typical package tying machine, like those briefly described above to illustrate the present invention, has a rigid twine wrapper arm, rotatably mounted above and to the rear of the package wrapping table of the tying machine. In order to permit the running speed of the twine to catch up to the almost instantaneously achieved full rotational speed of the wrapper arm, and further, to automatically take up slack in the twine as it is being fed and wrapped about the package by the tying machine, the flexible drawback assembly of this invention is non-rotatively mounted on the wrapper arm near the latter's axis of rotation. Because the flexible drawback assembly of this invention can simultaneously deflectably change its own angle of operation in relation to the wrapper arm as well as exert the necessary take-up force on the twine, it is able to quickly operate through an increased travel range. Furthermore, because the drawback assembly of this invention is of relatively light construction, its effective operating length can be extended without being detrimentally affected by centrifugal forces, thereby allowing greater slack take-up.

The preferred embodiment of the present flexible drawback assembly comprises a laterally deflectable resilient flexor means in the form of a coil spring having an extended free ended arm terminating in a loop or eyelet which acts as a guide for the tie material, such as twine. The other or inner end of the spring is rigidly affixed to the wrapper arm of the package tying machine in much the same fashion as prior art drawback levers, but without any direct limitation on its range of operating positions. The anchored, non-pivotal connection of the flexible drawback lever of this invention to a tying machine's wrapper arm allows only lateral lever movements, viz, deflections bending the lever laterally of its normal longitudinal axis and made about its fixed end. Such sidewise bending action of the lever of the present invention is in contradistinction to the freely pivotal movements of the rigid prior art levers, which were limited only by the previously mentioned angularly extending fingers. Because of the relative simplicity of the preferred embodiment of this invention, the manufacturing costs and overall number of parts are considerably reduced. Furthermore, due to the dramatically increased operational ranges of the improved drawback assembly of this invention, very small packages may be wrapped on a large tying machine as well as the customary large packages thereby permitting the use of a single size machine for handling a range of package sizes which previously required several different machine sizes according to the prior art.

One of the principle objects of this invention is to provide an improved drawback assembly for use with package tying machines capable of taking up variable amounts of twine slack to thereby expand the range of package size operation for the tying machine.

It is another object of this machine to provide a drawback assembly for a package tying machine of simple,

operationally dependable construction and leading to reduced manufacturing and maintainance costs.

This invention has as a further object the provision of a drawback assembly capable of operating directly on the tie materials through an increased arc of travel.

It is a still further object of this invention to provide a drawback lever as aforesaid having a construction that it is only minimally affected by centrifugal forces, thereby permitting increased drawback lever length and resultant greater operating capabilities.

These and other objects, features and advantages of this invention will become apparent from the following detailed description of a preferred embodiment thereof illustrated in the accompanying drawings in which:

FIG. 1 is a partial perspective view from the front side of a typical package tying machine embodying this invention;

FIG. 2 is a front fragmentary view of the flexible drawback mechanism of this invention and indicating various operating positions therefor; and

FIG. 3 is a fragmentary top view of the flexible drawback of FIG. 2.

DESCRIPTION OF THE PREFERRED EMBODIMENT

Referring now to FIG. 1, there is partially illustrated and generally denoted by reference numeral 11 a typical package tying machine with which this invention is useful. The tying machine 11 includes a base and support structure (not shown), a planar package wrapping table 13, and a support bracket 15 which is mounted at the rear of the machine 11 and which extends above the level of the wrapping table 13. Carried by the support bracket 15 and bearingly supported thereby is a drive shaft 17. Securely connected to the drive shaft 17, such as by any well-known key and keying means (not shown), is a wrapper arm hub 19 (see FIG. 3) having a drive gear 21 formed integrally therewith for rotationally driving the wrapper arm hub 19 about the axis of the drive shaft 17. Suitable starter means and motor driving means (not shown) are located within the base support structure of the tying machine 11 and a drive gear chain 23 connects the driving motor with the drive gear 21. A wrapper arm support 25, in the form of a radial extension of the wrapper arm hub 19 securely carries a rigid twine wrapper arm 27 which is of sufficient length that it is able to wrap a reach of any tie material, such as twine 29, around a bundle or package 31 placed on table 13. Plural string eyelets 33 are mounted on the twine wrapper arm 27 for guiding the twine 29 from a supply (not shown) through a pay out hole 35 to the wrapper arm guide 37.

The preferred form of the flexible drawback assembly of this invention, generally denoted by reference numeral 40 is securely and non-pivottally fastened to the wrapper arm support 25 by means of a machine bolt 41 as seen in FIGS. 2 and 3. Assembly 40 comprises a connector stem 43 having an outer end receptive of the bolt 41 for connection to arm hub 19, a coil spring body 45, and an extended drawback lever 47 which terminates in a string-guide eyelet 49 at its outer end.

It will be noted that the connector stem 43, the coil spring 45, the drawback lever 47, and the eyelet 49 are all formed in coaxial alignment preferably of a continuous piece of material, such as suitable spring metal, so as to result in a very simple construction. It further will

be understood by one skilled in this art, however, that the flexible drawback assembly may be formed of multiple pieces suitably interjoined, and alternatively, different laterally deflectable flexor means can be substituted for coil spring 45.

In order to maintain the assembly 40 in an operational plane generally parallel to the operational plane of the wrapper arm 27 during rotational movement thereof, a deflector shield 51 is securely mounted by means of the bolt 41 between the connector stem 43 and the wrapper arm hub 19. The deflector shield 51 may be mounted in a specific angular relationship to the twine wrapper arm 27, as best seen in FIG. 2, such that the spring 45 is given lateral support in one lateral direction for all of its operating positions, as will be explained in greater detail presently. In this fashion, the effective length-of-drawback of assembly 40 is maximized because the same is restrained from swinging side to side in operation. Furthermore, the deflector shield 51 prohibits the operating end of flexible assembly 40 i.e., guide eyelet 49, from fouling the rotational wrapping of the twine 29 by wrapper arm 27.

Turning now to a description of the overall operation of the flexible drawback assembly of this invention, there are shown in FIG. 2, several of its operating positions. The position of the drawback lever, shown in dashed lines, at 47a which is at the most extreme angle to the twine wrapper arm 27 is its position when the tying machine 11 is at rest and with a minimally adequate tension in the twine 29. This position is also assumed when the knotting operation is being performed on the package 31, during which the twine wrapper arm 27 is at rest and the flexible drawback assembly is providing the necessary relaxed tension on twine 29. Such position also occurs when very small packages are being wrapped, so that while the twine wrapper arm 27 is under a rotational wrapping movement, assembly 40 is taking up maximum twine slack.

The laterally deflected position of drawback lever 47 which is shown in dashed lines at 47b is one of generally parallel alignment with twine wrapper arm 27. This position for lever 47 occurs when the tying machine 11 is initially actuated to wrap a reach of twine around the package 31. Because the twine wrapper arm 27, when engaged at the beginning of a typical wrapping and tying operation, is accelerated almost instantaneously from its rest position to its maximum rotational speed, any drawback assembly must be capable of permitting quick following movement of the twine with very little drawn back or tensioned. This is because all available twine 29 is needed for wrapping the package 31 by twine wrapper arm 27, which is at full rotational speed, requiring the twine to move from a zero running speed to match the movement of the wrapper arm. Accordingly, to do otherwise breaks the twine 29. The lever 47 directly and quickly assumes this generally parallel alignment, as illustrated in FIG. 2, because of the lateral deflection capabilities provided by coil spring 45.

When the running speed of the twine (which was originally at rest) catches up to the full rotational wrapping speed of the wrapper arm 27, the assembly 40 quickly reacts and begins to function as a twine tensioning and slack take-up device with the lever 47, moving toward its normal operating position as shown in solid lines in FIG. 2. It will be understood that during the normal rotational operations of the twine wrapper arm 27 and the following reaction of lever 47, the latter

may assume any of the three positions shown in FIG. 2, as well as innumerable intermediate positions, depending on the type of tie medium used, the size of the package 31, the angular and locational placement of package 31 on wrapping table 13, and any other factors which influence the running tension in twine 29.

It can be readily seen that the non-pivotal connection of assembly 40 to arm 27 and the lateral deflection capabilities of spring 45 place inherent limitations on the degree of travel of assembly 40 from one operating extreme to the other in relation to wrapper arm 27. These features eliminate the need for any angular extending fingers, such as those disclosed in and required by above referred to U.S. Pat No. 2,371,024. Moreover, the flexible drawback assembly hereof more readily and easily allows for the instant take-up of slack occurring during tension changes on the twine medium, which feature is most desirable between the wrapping and tying cycles. Reference is made to U.S. Pat. No. 3,708,190, for a fuller discussion on the need to provide for such changes in the twine tension.

From the foregoing description of the preferred embodiment of this invention, it will be obvious to one skilled in the art that various changes, modifications and substitutions of equivalents can be made in the construction of the described flexible drawback assembly for a package tying machine without departing from the scope of this invention as defined in the appended claims.

I claim:

1. In a power-operated package tying machine of the type having a rotatably driven wrapper arm for encircling a reach of tie material about a package, a flexible drawback apparatus comprising: elongated flexor means having one end fixed to the machine's wrapper arm for rotational movement therewith, said flexor means being operable to resiliently deflect laterally of its longitudinal axis about said fixed end; lever means extending outwardly from the end of said flexor means opposite said one fixed end; and guide means at the terminal end of said lever means for slidably coupling the tie material thereto, whereby said flexible drawback

apparatus is operable to resiliently maintain tension on the tie material throughout operational movements of the wrapper arm.

2. The invention of claim 1, wherein said flexor means comprises a coil spring.

3. The invention of claim 1, wherein said lever means is fixedly connected in coaxial alignment with said flexor means.

4. The invention of claim 1, including deflector shield 10 means mounted between said flexor means and the wrapper arm for laterally stabilizing said flexor means in one lateral direction thereby to maintain said flexor means and the wrapper arm in parallel operational planes during rotational movements thereof.

5. A flexible twine drawback assembly for a bundle tying machine, comprising: twine means rotatably wrapped about a bundle by the power-driven wrapper arm of a bundle tying machine; coil spring means having one end securely anchored to said rotatable, power-driven twine wrapper arm, said coil spring means having the other end thereof formed to provide an elongated twine drawback lever, a twine guide formed at the terminal end of said lever for coupling said twine means thereto, said coil spring means being operable to deflect laterally about its anchored end thereby causing said extended lever and twine guide to maintain tension in said retained twine means and reactively take up slack variations occurring therein.

6. In a package tying machine, the combination comprising: a package wrapping table having support means; twine means, a rotatably driven twine-wrapping arm means for wrapping a reach of said twine means about a package on said table; and flexible twine drawback means having one end non-rotatively fixed to said twine-wrapping arm means to rotate therewith and having the other end thereof operable to translate laterally relative to said wrapper arm means to maintain tension on said twine means; said drawback means comprising interjoined laterally deflectible resilient flexor means, 35 extended lever means, and guide means on said lever means for slidably coupling said twine means thereto.
